The ornamental design for a combined purse and wallet, as shown and described.

DESCRIPTION

FIG. 1 is a front elevational view of a combined purse and wallet showing our new design;

FIG. 2 is a top plan view;

FIG. 3 is a rear elevational view;

FIG. 4 is a bottom plan view;

FIG. 5 is a left side elevational view; and,

FIG. 6 is a right side elevational view.

The broken line showing of a pencil in FIG. 1 is for illustrative purpose only and forms no part of the claimed design.
